WARNER W. SLAYBACK, OF PONCA CITY, OKLAHOMA.

GASKET-CUTTER.

1,254,544.

Specification of Letters Patent. Patented Jan. 22, 1918.

Application filed June 15, 1917. Serial No. 174,973.

To all whom it may concern:

Be it known that I, WARNER W. SLAYBACK, a citizen of the United States, residing at Ponca City, in the county of Kay and State of Oklahoma, have invented new and useful Improvements in Gasket-Cutters, of which the following is a specification.

This invention relates to implements for cutting sheets of felt and other like material into gaskets, and more especially to those which employ a sweep carrying rotary cutting knives; and the object of the same is to produce a device by means of which the outer circumference of the gasket and the inner circumference thereof may be cut to selective sizes, and which through special attachments may be employed for cutting gaskets from waste pieces of material which are smaller than the opening in the base of the instrument.

Details are set forth in the following specification, and reference is made to the accompanying drawings wherein;

Figure 1 is a perspective view of this implement at work. Fig. 2 is a vertical sectional view, showing the sweep and cutters in elevation.

Figs. 3 and 4 are sectional views of the washers.

The base 1 of this machine is annular, or at least it has a round opening through its center, and by preference it is externally round so that it constitutes a ring as best seen in Fig. 1. Its inner edge is rabbeted as at 2, or in other words the lower half of the inner edge is cut away leaving a flange projecting inward at the upper half thereof. On this base is mounted a skeleton frame 3 which may consist of two arches standing in planes at right angles to each other, their feet 4 riveted or otherwise secured to the base and their centers crossed or united and supporting a nut 5 which stands directly above the center of the annular base and whose threads are of very gentle pitch. Vertically the nut should be quite long so that it constitutes a tubular guide for the main shaft 6 which is threaded at 7 to correspond with the threads of the nut, above which it carries a crank 8 having a handle 9.

To the lower end of the shaft is secured a sweep 10 which is a bar of rectangular cross-section extending horizontally across the interior of the frame 3 and marked on its side faces with scales 11. Slidably mounted

on the two arms of said bar are sleeves 12 through which pass set screws 13 for holding them after they are adjusted along the scales, 11, and each sleeve carries a depending fork 14 in which at 15 is pivoted a rotary cutter 16.

With this construction, the crank is turned to rotate the shaft 6 reversely and run its threads 7 up through the nuts 5 so that the cutting edges of the cutters 16 are above the plane of the lower face of the base 1, and then the implement is laid over a sheet of material such as felt F as indicated in Fig. 1. The sleeves 12 are set at proper distances as seen in Fig. 2, and now when the crank handle 8 is turned to rotate the shaft, the entire sweep is moved around within the frame and downward slowly by means of the gentle threads 7, and eventually the edges of the cutters 16 come in contact with the work F and a gasket is cut out of the latter, the innermost rotary cutter 16 cutting its inner circumference and the outermost cutter its outer circumference according as the sleeves have been set. It is obvious that the piece of work F must be of sufficient size to underlie the base 1 and perhaps to extend beyond it as seen in Fig. 1.

It sometimes occurs that a small-sized gasket is to be cut, an old gasket is to be trimmed, or for some other reason the piece of work is not as large as the base, and means are therefore necessary to hold it down on the table or other support while it is being cut—a service ordinarily performed by the annular base as seen in Fig. 1. In order to thus practically or in effect reduce the size of the base, I make use of a plurality of washers, two of which are shown in Figs. 3 and 4. The larger washer 20 has its outer edge flanged at its lower half as at 21 to fit the rabbet 2 within the base 1, and its inner edge rabbeted as at 22. The smaller washer 30 also has its outer edge flanged as at 31 and its inner edge rabbeted as at 32. There might be a third and perhaps a fourth washer with a device of the size shown in the drawings, but the illustration is sufficient to convey the idea. The larger washer is adapted to fit within the base, and when in place it of course reduces the size of the opening in such base. The smaller washer 30 is adapted to fit within the larger washer, and when in place it reduces the size thereof in the same manner. The flanged outer edge of each movable ele-

- ment fits the rabbeted inner edge of the element next larger, or in other words the washers and the base constitute coating or nested members which are used or not as the case 5 may require. If now it is desired to cut a gasket from a small piece or scrap of material F, whose size is such that the annular base will not overlie it as seen in Fig. 1, one or more of these washers are inserted 10 and in effect the size of the opening in the base is thereby reduced. The cutters are now set along the scales 11 on the sweep 10 at proper points to define the inner and outer circumference of the gasket, and the 15 rotation of the crank handle 8 performs the work as above described. The use of the gentle threads 7 is obviously to permit the rotation of the main shaft and the sweep and at the same time to cause the down- 20 ward feed of the shaft and the cutters when the crank handle is turned to the right. After cutting a gasket, the crank handle is reversed in its direction of rotation and the shaft and the sweep and the cutters thereby 25 raised, ready for the next operation. The employment of a skeleton frame 3 permits the operator to reach through it any time and gain access to the set screws 13 so that sleeves may be adjusted inward or outward 30 or along the sweep-arms, without the necessity of disconnecting the parts. The device is by preference entirely of metal, and I do not wish to be limited to proportions or details.
- 35 What is claimed as new is:—
1. In a gasket cutter, the combination with an annular base, a skeleton frame mounted thereon, a nut carried by the center of the frame and axially in alinement 40 with the center of the base, the threads within the nut being of gentle pitch, and a main shaft threaded through said nut; of means at the upper end of the shaft for rotating it in either direction, a sweep 45 secured across its lower end and having grad-

uations marked on its arms, sleeves adjustably disposed on said arms, forks carried by the sleeves, and a rotary cutter mounted in each fork.

2. In a gasket cutter, the combination 50 with an annular base, a skeleton frame mounted thereon, a nut carried by the center of the frame and axially in alinement with the center of the base, the threads within the nut being of gentle pitch, and a main 55 shaft threaded through said nut; of a crank handle at the upper end of said shaft, a sweep secured across the lower end of the shaft and rectangular in cross-section, sleeves adjustably mounted on the arms of said 60 sweep, and rotary cutters carried by said sleeves.

3. In a gasket cutter, the combination 65 with an annular base rabbeted around its inner periphery, a skeleton frame mounted thereon and having a nut over the center of the base, a main shaft threaded through said nut and having operating means at its upper end, a sweep at the lower end of the shaft within the frame, and rotary cut- 70 ters carried by said sweep; of a plurality of washers whereof each has its outer edge flanged and its inner edge rabbeted, said washers and base making up a series of elements adapted to be nested, for the purpose 75 set forth.

4. In a gasket cutter, the combination 80 with an annular base, a frame mounted thereon, a shaft rotatably mounted through the axis of said frame, and the cutting 85 mechanism carried by said shaft; of a series of washers of different size making up with said base a set of nested elements, each flanged at its outer edge and rabbeted at its inner edge whereby the elements may be interengaged and applied as required.

In testimony whereof I affix my signature.

WARNER W. SLAYBACK.
